UNITED STATES PATENT OFFICE.

JOSEPH H. SEBALD, OF EASTON, PENNSYLVANIA, ASSIGNOR TO A. S. CAMERON STEAM
PUMP WORKS, OF NEW YORK, N. Y., A CORPORATION OF NEW JERSEY.

MULTI-IMPELLER SINGLE-STAGE CENTRIFUGAL PUMP.

1,158,569

Specification of Letters Patent. Patented Nov. 2, 1915

Application filed November 14, 1913. Serial No. 800,929.

To all whom it may concern:

Be it known that I, JOSEPH H. SEBALD, a subject of the Emperor of Austria-Hungary, having taken out my first naturalization papers in the United States, residing at 5 Easton, in the county of Northampton and State of Pennsylvania, have invented a certain new and useful Improvement in Multi-Impeller Single-Stage Centrifugal Pumps, 10 of which the following is a specification.

This invention relates to centrifugal pumps and more particularly to a multi-impeller single stage pump for use in pumping the water from the hot well of a con- 15 denser.

In the pumps which are at present generally used for removing the water from the hot well of a condenser and which are generally of the single stage type with a double suction central impeller, the stuffing boxes 20 in the bearings are always exposed on their inner faces to the water which is passing to the inlet of the pump and which, of course, is at the same pressure as the interior of the 25 condenser chamber which, in high vacuum condensers, is around 29" of vacuum. It has been found that in such cases it is very difficult to construct the stuffing boxes so that air does not come through into the suc- 30 tion chamber of the pump. When the water pumped is returned to the condenser, this air will lower the vacuum to an appreciable extent.

The object of the present invention is to 35 construct a pump which has the necessary stuffing boxes at each side and is so constructed that the inner ends of both these stuffing boxes are exposed, not to the pressure of the suction of the pump but to the 40 pressure of the pump discharge, which is at least that of the atmosphere and will not allow any air to be forced into the pump through the stuffing boxes. With this object in view, I have devised a pump a practical embodiment of which is shown in the 45 accompanying drawings in which:

Figure 1 is a side elevation which shows the suction and discharge pipes and Fig. 2 is a section through Fig. 1 on the line 50 II-II.

The pump, as shown, comprises a cylindrical casing 1 which is divided by partitions 2 into the central inlet chamber 3 into which the fluid to be pumped is drawn 55 through suction pipe 4 and volute impeller

chambers 5 which discharge through individual discharge pipes 6. Keyed upon a shaft 7 are impellers 8 which rotate in impeller chambers 5 and consist of disks 9, blades 10 and covers 11. The disks 9 are imperforate and the covers 11 bend around into sleeves 12 which engage the inner edges of partitions 2. Each of the impellers therefore has but a single suction opening which opens from the central inlet chamber 60 65. The shaft 7 is journaled in bearing boxes 13 which fit into cylindrical apertures in the sides of the casing 1. In the outer portions of the bearing boxes 13, which also serve as stuffing boxes, are stuffing glands which are provided with water seals 14 to which water is conveyed by passages 15 in the casing. The disks 9 are spaced a short distance away from the sides of the casing 1 so that a passage is provided which allows the water 70 under pressure from the discharge of the impellers to pass down and come in contact with the inner faces of the bearing boxes 13. In the inner portion of the boxes 13 are glands 16 which surround the shaft and are 75 connected by passages 17 to the casing so that water under pressure in the casing can enter the glands. Perforations 18 in the bushings 19 allow the water to contact with the surface of the shaft itself. 80 85

It will be evident that with the above described construction the inner faces of the boxes 13 will be at all times subjected to contact with water at the pressure of the pump discharge, this water being conveyed also to the glands 16 and the water seal 14. As the discharge pressure of the water is above that of the atmosphere it will be practically impossible for any air to come along the shaft or otherwise into the pump casing. 90 95

Although the pump here is shown with stuffing boxes which serve also as bearing boxes, it is evident that outside bearings could be provided and boxes 13 serve only as stuffing boxes. 100

It is to be understood that the present showing and description discloses only one specified modification of my invention and other forms and modifications are included in the spirit and scope of the invention as expressed in the claims. 105

What I claim is:

1. In a multi-impeller centrifugal pump, a casing comprising a central inlet chamber, and impeller chambers on each side of

said central chamber, covered impellers in said impeller chambers having inlets communicating only with said central chamber, a common shaft for said impellers, boxes in the outer faces of said impeller chambers, stuffing glands in said boxes, water glands surrounding said shaft inside of said stuffing glands and means for conveying fluid under pressure from the discharge of said 10 impellers to the impeller chambers contiguous to said boxes.

2. In a multi-impeller centrifugal pump, a casing comprising a central inlet chamber and impeller chambers on each side of said central chamber, covered impellers in said impeller chambers having their only inlets

opening from said central chamber, a common shaft for said impellers, boxes in opposite faces of said casing, stuffing glands having water seals in the outer parts of 20 said boxes, sealing glands surrounding said shaft in the inner parts of said boxes, and passages for conveying fluid under pressure from the discharge of said impellers to said glands and to the casing into contact with 25 the inner faces of said boxes.

In testimony whereof, I have hereunto set my hand.

JOSEPH H. SEBALD.
